UNITED STATES PATENT OFFICE.

JAMES N. FARLOW, OF OAKLAND, CALIFORNIA.

DESIGN FOR A FOLDING BED.

45,866.

Specification for Design.

Patented June 2, 1914.

Application filed April 11, 1914. Serial No. 831,334. Term of patent 3½ years.

To all whom it may concern:

Be it known that I, JAMES N. FARLOW, a citizen of the United States, residing at Oakland, in the county of Alameda and State of California, have invented a new, original, and ornamental Design for Folding Beds, of which the following is a specification, reference being had to the accompanying drawing, forming part thereof.

The figure is a view in perspective of a folding-bed, showing my new design.

I claim:—

The ornamental design for a folding-bed, as shown.

In testimony whereof I affix my signature in presence of two witnesses.

JAMES N. FARLOW.

Witnesses:
